UNITED STATES PATENT OFFICE.

CHARLES G. PERKINS, OF HARTFORD, CONNECTICUT, ASSIGNOR TO THE ARROW ELECTRIC COMPANY, OF HARTFORD, CONNECTICUT.

ROTARY SNAP ELECTRIC SWITCH.

No. 908,694.

Specification of Letters Patent.

Patented Jan. 5, 1909.

Application filed July 29, 1907, Serial No. 385,982. Renewed November 14, 1908. Serial No. 482,620.

To all whom it may concern:

Be it known that I, CHARLES G. PERKINS, a citizen of the United States, residing at Hartford, in the county of Hartford and 5 State of Connecticut, have invented a new and useful Rotatory Snap Electric Switch, of which the following is a specification.

This invention relates to an improvement in rotatory snap electric switches which are 10 provided with means for indicating the position of the movable contacts and the condition of the electric circuits in which the switches are connected.

The object of the invention is to provide 15 such a switch with an indicating means which is simple to construct, easy to apply and which instantly indicates the condition of the circuit in a very satisfactory and plain manner.

20 Figure 1 of the accompanying drawings shows a plan of a rotatory snap electric switch which embodies the invention. Fig. 2 shows a side elevation of the same switch with the cover, insulating lining for the cover 25 and the indicating means cut in central section. Fig. 3 shows a plan of the base of the switch with the stationary contacts omitted. Fig. 4 shows a view of the inside of the cover of the switch. Fig. 5 shows a plan of the indicating disk and shutter. Fig. 6 shows a reverse plan of the indicating disk and shutter. Fig. 7 shows a section of the disk and shutter. Fig. 8 shows a section of the shutter and lining connected in a different manner. 35 Fig. 9 shows a plan of the lining and an indicating dial arranged according to this invention.

The base 1 of the switch is preferably 40 formed of a circular block of porcelain or other suitable insulating material. The actuating spring 2 is mounted upon the spindle 3 which is provided with the usual turn button or handle 4. The locking and releasing mechanism can be of any common construction and as it forms no part of the present invention it is not illustrated. As the handle 45 is turned the spring is made tense and when the locking mechanism is released the spring throws the movable contact plate 5, which is loosely mounted upon but insulated from the 50 posts 6, in the usual way. The cover 7 is preferably formed of sheet metal, and inside of the cover is an insulating lining 8 which is usually formed of insulating fiber or paper.

The indicating means preferably consists 55 of a thin disk 9 of white paper and an oblong

shutter 10 of black sheet metal which is free to move around on the surface of the light disk. It is preferred to fasten the shutter to a washer 11 by means of eyelet-studs 12 that are struck up out of the washer. The shutter and the washer connected in this manner loosely hold the disk and the shutter together but permit the shutter to be turned in front of the disk. Of course the disk could be black and the shutter white if desired. The 60 eyelet-studs which are employed to connect the washer and the shutter are arranged so that the posts which carry the movable contacts will project through the eyelets, and as the movable contacts are thrown these posts 65 will turn the shutter with them.

In the face of the cover is an observation 70 opening 13. As the handle is turned and the movable contacts and shutter are thrown, the space back of this opening alternately 75 appears light and dark, that is, if the shutter is back of the opening the space shows dark and indicates that the circuit is open, but if the shutter is not back of the opening the space shows white and indicates that the circuit is closed and lights are burning. This 80 of course is the action if the shutter is black and the disk is white. If the disk is black and the shutter is white, the reverse is true, that is, when the shutter is back of the opening the space shows white and when the shutter is not back of the opening the space 85 shows dark. This form of indicating means is dropped into the cover and then the insulating lining is placed in position. The lining 90 not only insulates the cover but retains the disk and shutter in position. When the cover is applied to the base it is turned until the posts which support the movable contacts will pass through the openings in the 95 studs which hold the disk and shutter together, then the handle is screwed upon the spindle in the usual manner so as to hold the cover in place.

If desired the shutter can be loosely attached directly to the lining instead of to a separate disk, as shown in Fig. 8, in which case the outer face of the lining would be of a contrasting color to that of the shutter, for instance, the outer face of the lining may be 100 black, and the shutter white, or the outer 105 face of the lining could be white and the shutter black, so that as the shutter was turned with the movable contacts, the space back of the opening through the cover would alter- 110

nately show light and dark. In this case the shutter 14 may be laid in a recess in the lining 15 and held in place by eyelet-studs 16 which are struck up from a washer 17.

5 As shown in Fig. 9, instead of employing a shutter which is the preferred form, a dial 18 lettered "Off" and "On", or with similar indications can be used, and this dial may be provided with openings 19 for the posts and 10 attached to the lining 20, in the manner above described.

The invention claimed is:

1. The combination with the actuating mechanism of a rotatory snap electric switch 15 of a movable contact, posts holding the movable contact, a cover with an indicating opening, an insulating lining for the cover, and a shutter of contrasting color having openings adapted to receive the posts and to be 20 moved therewith between the lining and the cover inside of the opening, substantially as specified.

2. The combination with the actuating mechanism of a rotatory snap electric switch 25 of a movable contact, posts supporting the movable contact, a cover with an indicating opening, an insulating lining for the cover, a disk arranged between the lining and the cover, and a shutter of a color contrasting

30 with that of the disk, provided with openings for receiving the posts and movable outside of the disk and inside of the cover so as to cause the space back of the opening through the cover to alternately appear light and dark, substantially as specified. 35

3. The combination with the actuating mechanism of a rotatory snap electric switch of a movable contact, posts supporting the movable contact, a cover with an indicating opening, an insulating lining for the cover, 40 and an indicating means provided with openings for receiving the posts and held in place inside of the cover by the insulating lining, substantially as specified.

4. A cover for a rotatory snap electric switch 45 comprising a metallic shell with an indicating opening, an insulating lining for the shell, and indicating means consisting of a disk and a shutter movable outside of the disk and inside of the cover, said disk and shutter being of contrasting color, and said shutter having openings for receiving the means which cause it to move, substantially as specified. 50
